UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 11,995, dated October 26, 1880.

Application filed July 31, 1880. Term of patent 3½ years.

To all whom it may concern:

Be it known that I, EDUARD LEISSNER, of New York, in the county and State of New York, have invented a new and original Design for Wall-Paper, of which the following is a specification.

This invention relates to a new and original design for wall-paper and similar fabrics.

It consists in a novel grouping and configuration of figures hereinafter more fully described.

The accompanying photograph illustrates a face view of wall-paper having my new design.

Upon the background *a* are placed lozenge-shaped figures *A*, irregularly dotted, over which are twined branches *B*, having leaves *c*, which are dimly perceptible. Fanciful scrolls *C*, of

peculiar outline, are placed above the branches *B* and leaves *c* at regular intervals, and partly cover the lozenge-shaped figures *A*, as shown 20 in the accompanying photograph.

I claim—

1. The design for wall-paper, consisting of the branches *B*, having leaves *c*, and lozenge-shaped figures *A*, substantially as shown. 25
2. The design for wall-paper, consisting of the scrolls *C*, shaped substantially as shown.
3. The design for a wall-paper, consisting of lozenge-shaped figures *A*, branches *B*, leaves *c*, and scrolls *C*, substantially as shown.

EDUARD LEISSNER.
